UNITED STATES PATENT OFFICE

2,496,495

PENCIL POINTER

John E. Riker, Detroit, Mich.

Application March 15, 1946, Serial No. 654,699

3 Claims. (Cl. 120—89)

1

This invention relates to pencil sharpening devices, and particularly to a device for pointing pencils especially adaptable for use by a draftsman.

Heretofore, the operation of sharpening or pointing a pencil has been objectionable because it required two hands to point the pencil, was time consuming and usually made it necessary for the draftsman to change his position or stance to avoid getting the particles of graphite on the drawing sheets. When long lines were being drawn, such as by the use of straightedges or triangles, the sharpening operation usually required the repositioning of the drafting tools before completing the lines. As a result of all these difficulties, the draftsman tended to sacrifice quality of workmanship rather than sharpen and point his pencil as often as he should.

An important object of this invention is to provide an improved device for sharpening or pointing which can be operated by one hand without requiring the draftsman to shift his position or release the drafting tools and which considerably reduces the number of movements and conserves time.

Another object of this invention is to provide a novel pencil pointing device which will provide either a conical point or a wedge-shaped point as desired with a minimum amount of effort. A further object of this invention is to provide a novel device of this character which is economical to construct and assemble and which may be located in a readily accessible position on the drafting table or other nearby support.

More specifically, an important object of this invention is to provide a novel pencil pointing device which by stroking a pencil in one plane will produce either a wedge-shaped or conical point depending upon how the pencil is held and manipulated. A feature of the invention is the provision whereby both faces of a wedge-shaped point may be cut in the same stroke of the pencil. Another feature of the invention is the provision of novel means for constraining the pencil as the point thereof is drawn through the device to a movement in one plane for producing the proper angle for the sides of a conical point. A further feature of the invention is the provision and location of wiping means which enables the draftsman to finish the sharpening stroke by drawing the point over the wiping substance.

Various other objects, advantages and meritorious features will become more fully apparent from the following specification, appended claims and accompanying drawings wherein:

2

Figure 1 is a top plan view of a pencil pointing device embodying the present invention,

Figure 2 is a cross sectional view along line 2—2 of Figure 1,

5 Figure 3 is a top view of a portion of the device showing the manner of removing the covers of the dust collecting receptacle,

10 Figure 4 is a vertical longitudinal sectional view through the device along line 4—4 of Figure 1 showing in dotted outline the positions of the pencils to obtain either a wedge-shaped or conical point,

Figure 5 is a vertical cross section view of the device along line 5—5 of Figure 1, and

15 Figure 6 is an enlarged sectional view of one end of the device along line 6—6 of Figure 4,

In the embodiment of the invention illustrated in the drawings, the device is constructed for removable attachment to the top of a drafting 20 table or nearby support. For this purpose it is provided with a base 10 provided at the opposite ends thereof with apertures 12 to facilitate attachment. The major portion of the length of the base intermediate the end sections thereof

25 supports the elongated receptacle of general rectangular formation. Two correspondingly shaped side walls 14—14 extend parallel to one another along the opposite sides of the base as shown in Figure 2. Two correspondingly shaped end walls

30 16—16 complete the assembly of the receptacle. Each end wall is provided with an upwardly opening V cut in which are supported the ends of the members carrying the pencil point sharpening means.

35 Extending the length of the receptacle on substantially the longitudinal median line thereof and in spaced relation to the side walls and the bottom thereof are two members 18 and 20. These members extend at an angle to one another to

40 form a V shaped groove or channel opening through the top of the device as shown in Figs. 2 and 5. The V cuts in the end walls of the receptacle receive the ends of the members 18 and 20 and assist in supporting the two members at the desired angle. The ends of the channel contain corresponding triangular or wedge-shaped blocks 22—22 having the inclined faces thereof extending at the same angle as the members 18 and 20. These wedges are received in the channel with their apexes pointed downwardly toward the base 10. A bolt member 24 or any other suitable securing means extends vertically through each of these wedges 22—22 and is threadably engaged in the base member in the manner indicated in Figs. 2 and 4. An intermediate wall

26 may be provided for supporting the mid-sections of the members 18 and 20. The wall 26 is shorter in height than the end walls and may be generally triangularly shaped as shown in Fig. 5 and provided with an approximately upwardly opening V-shaped groove for receiving and supporting the bottom edges of the members 18 and 20.

The two members 18 and 20 are provided with cutting surfaces on their inside faces which produce the desired point on the pencil when the latter is pulled or drawn in one or more strokes through the V-shaped channel between the members. These cutting surfaces are shorter than the lengths of the members and are arranged in alternate staggered relationship. Any suitable means may be used for forming the cutting surfaces. As shown in the illustrated embodiment of the invention two steel file sections 28 and 30 are employed. Each file section extends for a portion of the length of the channel and they are arranged in alternate staggered relation to one another. The inside face of each member opposite the file carried by the other member is smooth providing a flat guiding surface. The pencil point as it is drawn through the channel is opposed on one side with a sloping cutting surface and on the other side with a smooth inclined surface. In place of the metal files shown, there may be substituted other types of cutting surfaces such as abrasive stones having the same general shape and relation of the files illustrated herein. It is understood that where the term "file" is used herein it is applicable to any suitable cutting surface which will sharpen the point of a pencil.

Referring specifically to the illustrated embodiment of the invention herein, each file section 28 or 30 is constructed with a length equal substantially to one half the distance of the channel. One file 28 is carried on the member 18; the other file 30 is carried on the member 20. The first file 28 occupies the left half of the channel as viewed in Fig. 1, and the other file 30 occupies the right half of the channel as viewed on the same figure. The inside face portion of each member opposite a file section is smooth.

It is preferred that each file be mounted in its respective member with the cutting face thereof substantially flush with the inside face of the member. Where metal file sections are used, as in the present embodiment of the invention, this is preferably accomplished by cutting a recess in the inside face of each member of a depth equal to the size and thickness of the file and embedding the file section therein. This is the condition illustrated in Figs. 2 and 5. The cutting face of each file will then extend flush with the face of the member in which it is carried.

For best cutting operations, it is preferred to mount each file section 28 and 30 in its respective member so that the bottom edge thereof substantially meets the plane of the inside surface of the other member. This constrains the inserted end of the pencil in the channel so that the extreme end of the point is brought into contact with the teeth of the file section at whatever angle the pencil may be held. The most desirable angle for mounting the members 18 and 20 in order to form wedge-shaped and conical points is approximately twelve degrees to the vertical. The angle therefore between each file cutting face and the opposed smooth surface is approximately twenty-four degrees. This, it has

been found, is the most satisfactory angle for making either a conical point or a wedge-shaped point.

A narrow opening or slot is provided between the adjacent bottom edges of the members 18 and 20 through which the graphite cuttings or particles removed from the pencil points fall to the bottom of the receptacle. This is accomplished by chamfering the lower marginal portion of each smooth surface section of the members and also the area below each file section. A chamfered or beveled marginal portion on the smooth area of the member 18 is indicated at 32 in Figure 4. A chamfered portion below the file on the same member is indicated at 34. The member 20 is similarly chamfered and when the two members are assembled together they cooperate to form a narrow slot between the lower adjacent edges of these members as shown in Figures 2, 5 and 6. This slot is referred to by reference numeral 36. The slot opens into the base of the receptacle and the graphite cuttings or dust fall therethrough to the bottom 10.

To prevent the dust from escaping from the receptacle until it is desired to empty the same, removable closure members are provided for sealing the upper openings of the receptacle which extend along the opposite sides of the members 18 and 20. As shown, two such closure members 38 and 40 are provided which have a slidably interfitting engagement with the side walls 14-14 and the outer faces of the two members 18 and 20. These cover members are capable of being slid from either end of the device in the manner illustrated in Figure 3. Any other suitable form of closure means may be used if desired.

Wiping means is provided for cleaning the point of the pencil at the completion of the sharpening operation. This wiping means may be any yieldable substance such as cotton batting. It is preferably located in one end of the channel or trough between the members 18 and 20, and preferably at that end at which the draftsman usually completes his pointing stroke. As shown, a wedge-shaped piece of cotton batting 42 or other suitable material is located at the right hand end of the channel as viewed in Figures 1 and 4.

Two different types of pencil points may be formed by this device. The wedge-shaped type is made by inserting the pointed end of the pencil at one end of the channel and holding it in upright vertical position as shown in dotted outline at 44 in Figure 4. The pencil is drawn through the channel to the other end thereof while maintaining it in vertical position and without rotation. One or more strokes of this character may be made. At the completion of the last stroke the point may be drawn over the cotton batting wiping it clean.

To make a conical point, the point of the pencil is introduced into one end of the channel at an angle preferably of approximately 45°. It is drawn through the channel at this angle and simultaneously spun or rotated by the fingers of the hand. A pencil pulled through the channel in this manner is indicated in dotted outline at 46 in Figure 4. At the finish of the last stroke, the point may be wiped clean by drawing the point across the cotton batting. In making either the wedge-shaped or conical point the depth at which the pencil enters the channel may be controlled by the fingers of the draftsman. If the pencil is held in the normal position between the first and second fingers of the

hand it may be drawn through the channel by a back hand motion and the depth controlled by the first joint of the second or middle finger.

The device is also capable of pointing all types of draftsmen's compasses. When pointing smaller types of these instruments, it may be necessary to remove one of the covers 38 or 40. This will provide clearance for the other leg of the compass to move through the opening in the top of the receptacle left by the cover.

All the parts of the device, with the exception of the file surfaces and the attaching elements such as the bolts, are preferably made of plastic material.

What I claim is:

1. A device for pointing pencils comprising, in combination, an elongated opened top receptacle, a pair of members substantially the same length as the receptacle, means mounting said members in the opened top of the receptacle in spaced relation to the bottom thereof and with the members disposed at an acute angle to one another to form an upwardly opening V-shaped channel along which the pointed end of a pencil may be drawn, a pencil pointing file on the inside surface of one of said members and extending for substantially one-half the distance of the channel, a second pencil pointing file on the inside surface of the other member and extending for substantially the remaining half of the channel in alternate staggered relationship to the first mentioned file, the inside surface portion of each member opposite the file of the other member being smooth to provide a flat guiding surface for the pencil points drawn therethrough, and the lower ends of said members being shaped to provide an elongated slot in the base of the channel through which the particles removed from the pencil points fall to the bottom of the receptacle therebelow.

2. A device for pointing pencils comprising, in combination, an elongated opened top receptacle including side walls, end walls, and a bottom, a pair of members of substantially the same length as the side walls of the receptacle, means mounting said members longitudinally in said receptacle in spaced relation to the side walls and the bottom thereof and at an acute angle to one another to form an upwardly opening V-shaped channel through which the point of a pencil may be drawn, a pencil pointing file mounted on the inside surface of one of said members in substantially flush relationship with said last surface and extending from one end of the channel to the middle thereof, a pencil pointing file mounted on the inside surface of the other member in substantially flush relationship to said last surface and extending from the middle of the channel to the opposite end thereof, the inside surface portions of each member opposite to the file of the other member being smooth to

provide a flat guiding surface for the pencil point drawn therethrough, means forming a narrow slit between the bottom adjacent edges of said members through which particles removed from the pencil point fall to the bottom of the receptacle, a closure member covering the space between the upper edge of each member and the adjacent side wall of the receptacle, and means providing endwise slidable movement of each closure member to expose the space covered by the same.

3. A device for pointing pencils comprising, in combination, an elongated receptacle of substantially rectangular formation including a bottom and upright parallel side walls and parallel end walls, a pair of members of non-metallic material of substantially the same length as said receptacle, a metal file section embedded on the face of one member and extending for substantially one-half the length thereof, a similar metal file section embedded on the face of the other member and extending for substantially one-half the length thereof, means supporting said members on the end walls of said receptacle so that the members extend on the longitudinal median line of the receptacle and at an acute angle to one another to form an upwardly opening V-shaped channel extending the length of the receptacle, said means supporting the members in spaced relationship to the side walls and the bottom of the receptacle and with the file sections on the inside of the channel in alternate staggered relation to one another, the portion of the inside face of each member opposite to the file section of the other member being smooth to provide a flat guiding surface, the lower edge of each smooth portion of each member being chamfered to form a narrow slot along the base of the channel through which the particles removed from the pencil points fall to the bottom of the receptacle, an open ended horizontal guiding track formed by the upper edge of each member and the upper edge of the adjacent side wall, and a closure element slidably fitting each track and capable of endwise slidable movement therein to expose the space normally covered thereby.
